UNITED STATES PATENT OFFICE.

WILLIAM F. KESSLER, OF AUBURN, INDIANA.

LID AND COVER HOLDER FOR CIGAR BOXES AND THE LIKE.

Application filed May 25, 1925. Serial No. 22,858.

This invention relates to improvements in lid and cover holders for cigar boxes and the like, and the objects of the invention are to provide an attachment applicable to a box having a hinged lid that may be readily attached thereto so that the lid will be sustained in a suitable open position to admit display of the contents of the box; to provide a holder applicable to a box and its lid so that the lid will be held at a fixed open position while the box is being lifted by its lid; and to provide an attachment applicable to the hinged lid of a box and including a glass cover for normally closing the box while the lid thereof is held open, and so that the glass cover will swing with the lid upon the hinge thereof when the lid is tilted back and thereby admit of access to the contents of the box.

These objects are accomplished by the construction illustrated in the accompanying drawings, in which:—

Fig. 1 is a perspective view of a box and a structure embodying the invention applied thereto; and

Fig. 2 is a cross section of a box to which the invention is applied, the glass cover for the box being omitted.

The characters appearing in the description refer to parts shown in the drawings and designated thereon by corresponding characters.

The invention comprises a pair of oppositely disposed clips 1 that embrace the corresponding opposite ends of the hinged lid 2 of a box 3, the clips being held in fixed relation with each other by a tie rod 4, each end of which is secured in a socket 5 on the front of the corresponding clip. Each clip 40 has formed in its outer edge a second enlargement 6 in which is rigidly secured one end of a grapple rod 7. Each clip also has a forwardly extending lip 8 at its lower end that forms a support for the rear edge 45 of a glass cover plate 9 which is positioned so as to normally close the top of the box when the lid thereof is open. Each grapple rod 7 has a hook 10 at its outer end that embraces the outer edge of the glass plate 50 and holds the plate so that its rear edge bears against the front faces of the clips 1 between the enlargements 5 and lips 8 there- 55 of.

In utilizing the invention, the ends of the lid at the free edge thereof are introduced

between the clips, and the clips are then slid downwardly upon the ends of the lid until their lips come into contact with the wall of the box to which the lid is hinged, and the glass cover 9 is positioned with its rear edge resting upon the lips 8 and beneath the enlargements 5 thereon. The grapples 7 are then hooked into engagement with the front edge of the glass plate so that the plate is thereby held firmly in fixed relation with the lid of the box. When the glass plate is in closed relation with the top of the box, the lid 2 is held by the clips in erect open position, and when the operator lifts the box by grasping the lid and tilts the lid 70 backwardly, the glass cover is swung open accordingly by the action of the grapples so that the contents of the box is thereby made accessible to the patron. When the box is replaced upon the counter and the lid is released, the glass cover automatically gravitates to its normal closed position while the lid is again returned to its erect open position.

The invention may also be employed for holding the lid of the box in a fixed open position, and omitting the glass cover. In this event the clips are applied to the lid as in the previous instance and the grapples are hooked over the front wall of the box, 85 the ends of the hook being sharpened so as to admit of being drawn into the wall when force is applied to the lid in tilting it backwardly. When the device is thus applied the box may be handled freely by grasping 90 the lid and lifting it about at will. If so desired, in this instance, one of the clips and its grapple and the tie rod 4 may be dispensed with, while the other clip and its grapple may be used alone.

What I claim is:—

1. A device of the class described, comprising a pair of oppositely disposed clips applicable to the corresponding opposite ends of the hinged lid of a box, each clip having an enlargement on its front adjacent its lower end and a forwardly extending lip at its lower end spaced from said enlargement, and a second enlargement on its outer edge; a tie-rod, the ends of which are secured respectively in the front enlargements of the corresponding clips; a grapple rod for each clip having a sharp pointed hook at one end and secured at its opposite end to the corresponding clip in the enlargement 110

at the outer edge thereof; and a glass plate cover for the box positioned beneath said grapple rods, its outer edge having engagement in the hooked ends of said grapple rods, and its inner edge being held between the front enlargements on said clips and the lips thereon, said rods being operable to engage the front wall of the box adjacent the upper edge thereof and limit the backward 10 swinging movement of the box lid when the glass cover is omitted.

2. In a device of the class described, a pair of oppositely disposed clips applicable to the corresponding opposite ends of the 15 hinged lid of a box; a tie-rod connecting said clips; and a grapple rod connected with and extending forwardly from each of said clips, the outer end of said grapple rod having a sharp-ended back turned hook engage- 20 able with the front wall of the box adjacent

the upper edge thereof and operable to hold the lid in erect open position.

3. An attachment for a box having a hinged lid therefor, comprising a pair of clips applicable to the corresponding opposite ends of the box lid; a tie rod connecting said clips and extending across the inner face of the lid adjacent to and spaced from the upper edge of the rear wall of the box; a glass plate cover for the box positioned 25 with its rear edge between said tie-rod and the top of the rear wall of the box; and a grapple rod in connection with and extending forwardly from each of said clips above said glass cover, the outer end of each 30 grapple rod having a sharp ended down-turned hook engaging the forward edge of said glass cover.

In testimony whereof I affix my signature.
WILLIAM F. KESSLER.
